UNITED STATES PATENT OFFICE.

JOHN SHANAMAN, OF ANNVILLE, ASSIGNOR OF ONE-HALF TO JONAS L. KNOLL, OF LEBANON, PENNSYLVANIA.

CAR-COUPING.

SPECIFICATION forming part of Letters Patent No. 295,588, dated March 25, 1884.

Application filed February 9, 1884. (No model.)

To all whom it may concern:

Be it known that I, JOHN SHANAMAN, a citizen of the United States, residing at Annville, in the county of Lebanon and State of Pennsylvania, have invented certain new and useful Improvements in Car-Couplings, of which the following is a specification, reference being had therein to the accompanying drawings, in which—

10 Figure 1 is a top view of one end of two car-frames having my coupling attached thereto. Fig. 2 is a vertical section of the same. Fig. 3 is an end view of one of the car-frames and couplings. Fig. 4 is a perspective view of the draw-head-carrying plates. Fig. 5 is a perspective view of the draw-head and operating-rod thereof.

15 My invention relates to automatic car-couplings; and the objects of my invention are to provide a draw-head with a link rigidly attached thereto, having its front edge in a vertical plane, and carrying a hook projecting sidewise through the opening in said link, as will be hereinafter described, and the invention 20 specifically set forth in the claims.

25 In the drawings, A represents what I designate as the "lower frame" of a freight-car, having the transverse sill A' and the longitudinal string-pieces A², of usual form. To the under side of the latter are secured two stirrup-plates, a, made of flat iron bars, having their middle portion bent downward to receive the ends of the draw-bar-supporting plates a² and a³. The middle portion of these 30 plates is made wider than their ends, and shoulders a⁴ are in this manner produced thereon to retain the plates a² a³ centrally between the stirrup-plates a. The inner plate, a², is perforated centrally at a⁵, to receive the 35 inner end, d, of the draw-head bolt D, while the central portion of the plate a³ is provided with a slot, a⁶, to allow the draw-head passing therethrough to have some lateral play while being coupled or uncoupled. The front of the 40 draw-head is made of a plate, D', standing with its front edge vertically, but rounded or bent to one side at d', and its central portion removed or provided with a slot, D², having its longest dimensions vertically; or, in other

50 words, the form of the draw-head front plate resembles the letter D, and through its central opening the hook D³ projects laterally. This hook is made integral with the draw-head bolt and its front plate, and is made strong enough to draw a train of cars while interlocked with the vertical plate of a similar draw-head projecting from the end of another car. The forward end of the draw-head bolt is supported by a flat metal strap, a⁷, secured to the under side of the transverse sill A'. In 55 coal-cars the draw-head bolt D is generally made to pass through an opening in the sill, as shown on the right-hand side of Figs. 1 and 2; but the length of the slot D² in the vertical front plate of the draw-head is of sufficient 60 size to receive the hook D³, projecting from the draw-head of the adjoining car, whether said car is heavily loaded or is empty.

To uncouple cars provided with my coupling, an eyebolt or rod, F, is connected with 65 or made to receive the draw-head bolt, and said rod is retained in suitable guides, f, parallel with the sill A', and an expansive wire spring, f², coiled upon the rod F, having one end abutting against the car-frame and the 70 other against the shoulder or enlarged portion f', has a tendency to force the draw-head plate D' of one coupling sidewise against its mate upon the adjoining car. On the right-hand side of Fig. 1 the spring f³ upon the rod 75 F is a retractive spring, and operates to draw the draw-head toward its mate.

To uncouple two cars after their bumpers have been brought close together, there is pivoted to the transverse sill A' at g a vertical 80 hand-lever, G, to the lower end of which is pivoted at g' a flat rod, g², the extremity of which bears against the side of the draw-bolt D, so that by pulling upon the handle G, or the upper portion of the lever G toward the 85 side of the car, one of the draw-head hooks, D³, is forced away and disconnected from the plate or vertical link D' of the companion draw-head. To retain the draw-head in this uncoupled position, there is pivoted at g³ to 90 the upper portion of the lever G a light rod, g⁴, upon the under side whereof a transverse groove or notch, g⁵, is formed, adapted to 95

come in engagement with the end of a latch-plate, d^3 , secured to the frame of the car, so that the cars can be coupled or uncoupled without requiring the brakeman to pass between them. If the brakeman is standing upon the sill A' , he can release the rod g^4 from the latch-plate d^3 by simply lifting said rod a very short distance with his foot, if desired.

Having now fully described my invention, I claim—

1. A car draw-head bolt, D, having integral therewith a plate, D', provided with a vertical slot, D², and a hook, D³, projecting through said slot, substantially as and for the purpose described.

2. The combination of a draw-head bolt, its vertically-slotted draw-plate, and hook projecting through the side of said draw-plate, with the eyebolt F and spring thereon, substantially as and for the purpose described.

3. The combination of a draw-head bolt, its vertically-slotted draw-plate, and hook projecting through the side of said draw-plate, with the lever G and rod g^2 , substantially as and for the purpose set forth.

4. The combination of a draw-head bolt, its vertically-slotted draw-plate, and hook projecting through the side of said draw-plate, with the lever G, rod g^4 , having notch g^5 , and latch-plate d^3 , substantially as and for the purpose described.

In testimony whereof I affix my signature in presence of two witnesses.

JOHN SHANAMAN.
